UNITED STATES PATENT OFFICE.

JAMES C. SANDS, OF DOVER, NEW JERSEY.

AUTOMATIC COUPLING.

No. 864,108.

Specification of Letters Patent.

Patented Aug. 20, 1907.

Application filed December 4, 1906. Serial No. 346,346.

To all whom it may concern:

Be it known that I, JAMES C. SANDS, a citizen of the United States, residing at Dover, in the county of Morris and State of New Jersey, have invented certain new and useful Improvements in Automatic Couplings, of which the following is a specification.

My invention relates to improvements in automatic couplings having particular reference to the coupling of train pipe systems including the steam, air and water mains, and has as the principal object thereof the coupling of the several mains without the necessity of manual manipulation.

In the following is described in connection with the accompanying drawings one embodiment of the invention, the features thereof being more particularly pointed out hereinafter in the claims.

In the drawings Figure 1 is a side elevation of two adjoining cars illustrating the respective coupling members in their engaging or coupled position. Fig. 2 is an enlarged side elevation of the coupling device illustrating the respective members in their normal or open position. Fig. 3 is an enlarged side elevation of the coupling devices illustrating the respective members in their engaging or locked positions. Fig. 4 is a detail plan view of the coupling heads. Fig. 5 is a detail side elevation of one of the coupling heads illustrating the application of the coupling arm and provided with a single port or passage lead. Fig. 6 is a detail side elevation of the coupling heads in their engaging or locked positions illustrating the application of the single port or passage lead. Fig. 7 is a detail side elevation of one of the coupling heads illustrating the application of the coupling arms provided with a plurality of ports or passage leads. Fig. 8 is a detail side elevation of one of the coupling arms, parts being broken away to more clearly illustrate the particular parts embodied therein. Fig. 9 is a vertical sectional view of the port or passage lead controlling valve illustrating in connection therewith the means of holding the respective coupling arms in a central engaging or locked position, the disengaged or normal position being shown in dotted lines. Fig. 10 is a longitudinal sectional view of the port or passage lead controlling valve. Fig. 11 is a detail longitudinal sectional view of the auxiliary port or passage lead controlling valve, the same being adapted to control the passage of air, steam, water, etc., through the manually operated controlling valve. Fig. 12 is a detail longitudinal sectional view of the manually operated controlling valve, the coupling heads being shown in end elevation. Fig. 13 is an enlarged side elevation of the coupling arm illustrating the application of two manually operated controlling valves showing the means of cutting out the automatic coupling head. Fig. 14 is a cross-sectional view on the line 14-14 of Fig. 13. Fig. 15 is a side elevation of the coupling arm supporting

means and means for holding said coupling arm in its disengaged or normal position, the engaged position being shown in dotted lines. Fig. 16 is a cross-sectional view on the line 16-16 of Fig. 15.

Similar numerals of reference indicate similar parts throughout the several views.

In the drawings 1 and 2 represent two adjoining cars supported by trucks 3 on tracks 4, said cars being joined together or attached to one another as at 5 by means of buffer coupling heads 6.

7 and 8 are coupling arms pivoted as at 9 in universal supporting bracket 10 mounted on the underside of the respective buffer coupling heads 6, said coupling arms 7 and 8 having cast therewith at their upper ends adjacent to the pivotal point 9 reception nipples 11 adapted to receive the flexible hose ends 12 of the respective steam, water, and air leads 13 of the train pipe system.

The coupling arms 7 and 8 assume the position as shown in Fig. 2 of the drawings when the cars are detached and are held in this position by means of 75 centering lugs 14 cast on the under side of the buffer coupling heads 6. Said coupling arms 7 and 8 have suitably fastened thereto, or cast therewith, at their lower ends engaging heads 15 and 16 comprising male and female members 17 and 18 having formed on their 80 extreme ends 19 packing lugs or cams 20 contacting with a binding surface 21 formed on the inner surface of the guiding heads 22 and 23. Engaging heads 15 and 16 have suitably cast therewith at the central portion thereof pins 24 having mounted on their outer ends 85 finding or following arms 25, the ends of said finding arms being flared outwardly as at 26. The object of the guiding heads and the finding arms is to provide means whereby the coupling heads are brought into positive engagement with one another. Coupling 90 heads 15 and 16 are provided with a meshing surface 27 slightly inclined or beveled as shown in the dotted line in Fig. 4 of the drawings, the same providing a locking means for the coupling arms when the cars are brought into engagement or their coupled positions. 95

The universal supporting brackets 10, as illustrated in Figs. 8, 9 and 10 of the drawings, comprises a supporting member 28 having fastened therewith a swivel head 29 and two downwardly projecting lugs 30 adapted to receive valve core 31 mounted in bearings 32 100 suitably cut in the lugs 30. Coupling arm 8 is loosely mounted on said valve core 31 and forms at the pivotal point thereof the valve casing 33. 34 is a sleeve adjustably mounted on one end of said valve core 31 adapted to receive a high tension spring 35 having a 105 projecting arm 36 and at its extreme end a reception hook 37 receiving at that point an engaging link 38 pivotally mounted in lever 39 which is in turn pivotally mounted in coupling arm 8 as at 40. 41 is a lug cast with said coupling arm 8 and is adapted to act as a stop 110

or means of limiting the movement of lever 39 when the tension in said spring 35 is required to hold the respective coupling arms in their normal positions. The position the arms and means for holding or supporting the same assume is shown in dotted lines in Fig. 9 of the drawings. Valve core 31 has suitably cut therein steam-port or lead 42, water-port or lead 43 and air-port or lead 44 adapted to register with corresponding passage-ways 45 in the coupling arms 7 and 8 when the cars come together or when the coupling arms are in their locked position. Passage-ways or by-passes 45 extend longitudinally through the coupling arms 8 and 9 and connect at their respective mouth portions 46 in the respective coupling heads 15 and 16.

15 47 are coupling heads mounted on or cast with coupling arms 8 and 9 at an intermediate portion thereof and have formed therein ports 48 connecting with corresponding ports or passage-ways 49 in the manually operated or hand valve 50 mounted transversely in 20 each of the respective coupling arms. The object of the above described hand valve 50 is to provide means whereby the adjoining cars may be coupled together by manual means when one of the cars has not applied thereto the automatic or self-coupling devices.

25 Referring to Fig. 13 of the drawings, coupling arm 8 is provided at an intermediate portion thereof with coupling heads 51 and 52 having embodied therein ports 53 connecting with ports 54 cut in valve core 55, said valve core finding bearing in coupling arm 8. Valve 30 core 55 has cast thereon at one end thereof a hand-lever 56. The object of using the two coupling heads is to provide means whereby one or more of the passage-heads may be connected with corresponding coupling heads or hand-manipulated devices when one of the 35 cars is not provided with the automatic or self-coupling devices.

The universal pivoted device or coupling arm supporting means as illustrated in Fig. 15 of the drawings comprises a swivel bearing 57 mounted in buffer coupling head 6 (not shown) and a flange 58 having cast therewith downwardly projecting lugs 59.

40 60 is the valve core the parts comprising same being as heretofore described. Coupling arm 8 is loosely mounted on said valve core 60 and has formed thereon 45 between the downwardly projecting lugs 59 a lug or stop 61 adapted to engage a corresponding lug or stop 62 cast with flange 58, the object of said lug 62 being to provide means whereby the coupling arm may have a limited movement when the said arm is in its downward position.

45 63 is a heavy coiled spring fastened at one end thereof in lug 64 cast with flange 58, the other end thereof being adapted to be fastened to pin 65 mounted in coupling arm 8.

55 66 is a reception member fastened to the under side of the buffer coupling head 6 by means of bolt 67, its under surface thereof being inclined upwardly as at 68 forming in the center thereof a reception socket 69 adapted to receive finding roller 70 loosely mounted 60 in lugs 71 cast with coupling arm 8. The object of said finding roller and the parts adjacent thereto is to provide means whereby the respective coupling arms may readily find their central positions, also means whereby the several coupling arms may be thrown out 65 of alignment with one another or when it is desirous

of cutting out one of the automatic or self-coupling devices and utilizing in their place the manually operated coupling means.

The operation of the device is as follows:—When it is desirous of coupling a train or plurality of cars coupling arms 7 and 8 mounted on the respective cars are in the position shown in Fig. 2 of the drawings. The cars are then brought into contact with one another and coupled together as at 5 by means of buffer coupling heads 6. During the above described operation 70 engaging heads 15 and 16 are brought into positive engagement by means of guiding heads 22 and 23 and finding or following arms 25 mounted on pins 24, the respective heads thereof assuming a temporarily locked position by means of cams 20 bearing on binding surface 21 in the respective coupling heads. When upon reaching the position illustrated in Figs. 1 and 3 of the drawings the collapsed or locked position causes ports or by-passes 42 in valve core 31 to register with passage leads 45 in coupling arms 7 and 8 and flexible hose ends 80 12 of the train pipe system 13 completing the connections from car to car. Upon the detaching or uncoupling of the cars the coupling arms will assume their upright or normal position and are held in direct alignment or in their central positions by means of the coiled 85 spring 35 and centering lugs 14.

If it is desirous of cutting out one of the self-coupling arms lever 39 is thrown off center releasing the tension in spring 35 and permitting the coupling arm to be swung under the body of the car preventing any possible fracture of the coupling arm. Furthermore, if one of the adjoining cars is not provided with the self-coupling arm the pipe system throughout the train may be coupled together by locking engaging or coupling heads 47 together in the well known manner. 90 The steam, water and air connections are made by manipulating hand valve 50.

The device shown in Fig. 15 of the drawings illustrates the preferred form of the coupling arm supporting and position controlling means.

It is obvious that the device as herein disclosed may be widely varied without departing from the spirit of the invention.

What I claim and desire to secure by Letters Patent of the United States is:—

1. A device of the character described including universally pivoted automatic coupling arms, means for holding said coupling arms in alignment with each other, coupling heads formed thereon, means cast therewith for guiding said coupling heads into one another, the movement of said coupling arms comprising the means of controlling by-pass controlling valves.

2. A device of the character described including universally pivoted automatic coupling arms, means for holding said coupling arms in alignment with each other, passage-ways formed in said coupling arms, coupling heads formed thereon, guides formed on said coupling heads, the engaged or locked position of said coupling arms comprising the means of opening passageway controlling valves in each of said coupling arms.

3. A device of the character described including universally pivoted automatic coupling arms, means for holding said coupling arms in alignment with each other, passage-ways formed in said coupling arms, coupling heads formed thereon, guides formed on said coupling heads, the disengaged or normal position of said coupling arms comprising the means of closing passageway controlling valves in each of said coupling arms.

4. A device of the character described including a uni-

- versally pivoted automatic coupling arm, a plurality of ports formed therein, coupling heads formed thereon, means for connecting said ports with a plurality of hose end connections, and means for connecting said plurality of ports at an intermediate portion of said arm with a plurality of manually operated valves. 5
5. A device of the character described including a universally pivoted automatic coupling arm, a bearing therefor, means for holding said arm in a central position, a plurality of ports formed therein, a coupling head cast therewith comprising an engaging head, a guiding arm formed on one side thereof and a finding arm formed on the other side thereof. 10
6. A device of the character described including a universally pivoted automatic coupling arm, a bearing therefor, means for holding said arm in a central position, a plurality of ports formed therein, a coupling head formed thereon, guiding and finding means formed on said coupling head, manually operated coupling heads cast with said coupling arm, and means for connecting said manually operated coupling heads with said aforesaid plurality of ports. 15
7. A device of the character described including a universally pivoted automatic coupling arm, a bearing therefor, means for holding said coupling arm in a central position, a plurality of ports formed in said coupling arm connecting with a plurality of openings in a coupling head, and a plurality of ports formed in said bearing adapted to register with the plurality of ports in the coupling arm when the coupling arms are in their engaged or locked positions. 20
8. A device of the character described including a universally pivoted automatic coupling arm, means for holding said coupling arm in a central position, said holding means comprising a coiled spring wound about the bearing of said coupling arm, and means for retaining the tension in said coiled spring. 25
9. A device of the character described including a universally pivoted automatic coupling arm, means for holding said coupling arm in a central position, said holding 30
- means comprising a coiled spring wound about the bearing of said coupling arm, and means for releasing the tension in said coiled spring. 35
10. A device of the character described including a universally pivoted automatic coupling arm, means for holding said coupling arm in a central position, said holding means comprising a spring bearing against the universally pivoted coupling arm at one end thereof, the other end thereof finding bearing in a manually operated locking means. 40
11. A device of the character described including a universally pivoted automatic coupling arm, coupling heads formed thereon, said coupling heads comprising a guiding arm on one side thereof, a finding arm on the other side thereof, a locking surface formed thereon, and an inclined reception surface adapted to receive a corresponding coupling head. 45
12. A device of the character described including a universally pivoted automatic coupling arm, said universal pivot comprising a body portion, a bearing member, a valve core mounted in said body portion adapted to receive said coupling arm and form at that point the valve casing. 50
13. A device of the character described including a universally pivoted automatic coupling arm having mounted at an intermediate portion thereof a finding roller adapted to engage a centering block mounted on a separate body thereof. 55
14. A device of the character described including an automatic coupling arm, means for holding it in a central position, a universal pivot therefor, coupling heads mounted on said arm, fluid passageways formed therein, a valve associated with said fluid passageway, and a spring adapted to hold said coupling arm in disengaged position. 60
- In testimony whereof I have hereunto signed my name in the presence of two subscribing witnesses. 75
